PUMP

James K. Douglas, Milwaukee, Wis., assignor to
The Oilgear Company, Milwaukee, Wis., a corporation of Wisconsin

Application January 24, 1931, Serial No. 510,965

4 Claims. (Cl. 103—38)

This invention relates to positive displacement pumps which have two relatively rotatable parts arranged one within the other and the coacting surfaces thereof separated by a lubricating film which is maintained therein by the working fluid of the pump and subjected at all times to pump pressure.

Such pumps are frequently employed to perform work which requires the highest possible degree of accuracy in the delivery rate of the pump during a wide variation in certain factors which tend to change the delivery rate, such as variation in the viscosity of the working fluid, due to temperature changes, and variation in the pressure of the working fluid due to variation in the resistance encountered thereby.

The working fluid is ordinarily a good quality of lubricating oil which provides a satisfactory film between the coacting surfaces of the relatively rotatable parts but which varies in viscosity in accordance with the variation in the temperature thereof.

The clearance between the coacting surfaces of the relatively rotating parts is ordinarily sufficient to allow a film of oil in its heaviest or most viscous state to be formed therein and, as this film is subjected to pump pressure and as the parts rotate relatively to each other when the pump is in operation, a small volume of oil leaks from between these parts and another small volume passes from the discharge side of the pump to the intake side thereof so that the volume of oil delivered to an external circuit is less than the volume of oil which passes through the pump.

The total volume of oil which is lost by leakage and by passing from the discharge side of the pump to the intake side thereof is generally designated as the slip of the pump, that is, the slip of a pump is the difference between the volume of oil pumped by the pump and the volume actually delivered thereby to an external circuit.

At room temperatures and under low pressures, this slip is negligible relatively to the volumetric capacity of the pump but it increases in response to increases in pressure and temperature, the increased pressure forcing the oil more rapidly from between the relatively rotating parts and the increase in temperature reducing the viscosity of the oil and allowing it to flow more rapidly from between the relatively rotating parts at any given pressure.

For the purpose of illustration, the invention has been shown embodied in a pump which has its cylinders arranged radially in a cylinder barrel journaled upon a central shaft or pintle, its pis-

tons reciprocated in the cylinders and the cylinder barrel rotated upon the pintle by a circular driver which engages the outer ends of the pistons and has its axis of rotation eccentric to the axis of the pintle, and the working liquid delivered to and discharged from the cylinders through ports and passageways formed in the pintle. A pump of this character is fully illustrated and described in Patent No. 1,753,562 issued April 8, 1930 to John P. Ferris.

The pump disclosed in the above patent has been extensively and successfully used but, when it is employed to operate the hydraulic feeds of certain machine tools, the variation in slip precludes the possibility of accurately and uniformly maintaining a finely graduated feeding speed.

As an illustration, a pump of the size which is ordinarily employed to operate machine tool feeds has a slip of about 20 cubic inches per minute at moderate temperatures and pressures, but temperatures and pressures are often created which cause the slip to increase to 30 cubic inches per minute.

A variation in slip of 10 cubic inches is small relatively to the volumetric capacity of the pump but it often happens that a delivery of only 20 cubic inches per minute is required to produce a desired feeding speed and then a variation of 10 cubic inches in slip will cause an error of 50% in the feeding speed.

In order to reduce slip and to maintain the net delivery of the pump as constant as possible, the clearance between the pintle and the cylinder barrel has been reduced far below that ordinarily allowed between relatively rotating parts of corresponding diameters, and devices responsive to an increase in pressure have been provided for increasing the stroke of the pump to compensate for the increase in slip caused by the increase in pressure.

It has been found, however, that it is necessary to compensate for variations in both pressure and temperature in order to maintain the net delivery of the pump constant.

An object of the invention is to provide a pump having a net delivery which remains substantially constant throughout a wide range of variation in temperature and pressure.

Another object is to provide a positive displacement pump which is self-compensated for slip.

The invention is exemplified by the pump illustrated in the accompanying drawings in which the views are as follows:

Fig. 1 is a central vertical section through a

pump in which the invention is embodied, certain parts being shown in full and other parts partly broken away.

Fig. 2 is a schematic drawing illustrating the 5 hydraulic circuit of the pump.

Fig. 3 is a transverse section on the line 3—3 of Fig. 1.

Fig. 4 is a transverse section on the line 4—4 of Fig. 1.

10 Fig. 5 is a longitudinal section on the line 5—5 of Fig. 3.

The pump chosen for illustration is of the same type as the pump shown in Patent No. 1,753,562 referred to above, and the characteristics which 15 are common to both pumps have not been illustrated in detail nor extensively described herein.

The pump mechanism is arranged within and supported by a casing 1 having a liquid reservoir 2 in the lower part thereof and its front closed 20 by a plate 3 in which the outer end of a pump shaft 4 is journaled.

The shaft 4 is provided at its outer end with means, such as a pulley 5, for connecting the pump to a prime mover and has its inner end connected 25 to the driver 6 of a variable displacement pump. The driver 6 is journaled in an anti-friction bearing 7 which is carried by a bracket 8 attached to the front plate 3, thereby rotatably supporting the inner end of the shaft 4.

30 The bracket 8 has a gear pump chamber 9 formed therein and closed at its front by the front plate 3 to enclose a gear pump which has its driving gear 10 fixed upon the shaft 4 and its driven gear 11 arranged upon a stub-shaft 12 carried by the bracket 8.

The gear pump, which has a larger volumetric capacity than the variable displacement pump, has its intake connected to the reservoir 2 by a suction pipe 13 and its outlet connected by a low 40 pressure supply pipe 14 to the intake of the variable displacement pump and to a control valve 15 which is arranged in the front plate 3. The pressure of the liquid delivered by the gear pump is limited by a relief valve 16 through which excess 45 liquid is exhausted, as shown diagrammatically in Fig. 2.

The relief valve 16 exhausts into a chamber 17 which is formed in the bracket 8 and communicates with the chamber 9 and with the front bearing of the shaft 4 so that liquid delivered to the chamber 17 may form a liquid seal around the gear pump and lubricate the shaft bearing, as fully disclosed in the patent referred to above. The upper part of the chamber 17 has an overflow pipe 18 connected thereto through which liquid is returned to the reservoir 2.

The driver 6 has a number of segmental flanges 19 arranged around its outer periphery for reciprocating an equal number of hollow pistons 20 in their cylinders 21 which are formed in a cylinder barrel 22 and arranged in radial alignment with the flanges 19, the cylinder barrel 22 being journaled upon a pintle 23 which is arranged eccentric to the axis of the driver 6 when the pump is delivering liquid.

65 Each of the pistons 20 has a push pin 24 secured loosely therein and provided upon its outer end with a crosshead 25 which bears against an anti-friction bearing 26 arranged between it and a hardened bearing plate 27 carried by the corresponding flange 19.

The inner face of each crosshead 25 bears against the flattened periphery of an annular flange 28 which is formed on the driver 6 concentric to its axis of rotation and provided op-

posite each flange 19 with an opening 29 through which a push pin 24 extends.

Each of the cylinders 21 has a port 30 formed in the inner end thereof to register alternately with a segmental intake port 31 and a segmental discharge port 32 which are formed diametrically opposite each other in the pintle 23.

When the driver 6 is rotated, the cylinder barrel 22 is rotated and, if the pintle 23 is positioned eccentric to the axis of the driver 6, the pistons 20 upon one side of the pintle 23 are drawn outwardly by the flange 28 and the pistons 20 upon the other side thereof are forced inwardly by the flanges 19.

The outwardly moving pistons 20 draw liquid into their cylinders 21 through the ports 30 and 31 and the inwardly moving pistons 20 expel liquid from their cylinders 21 through the ports 30 and 32, the volume of liquid delivered by the pump depending upon the position of the pintle 23 relative to the axis of the driver 6.

The pintle 23 is carried by a rock arm 33 having a sleeve 34 arranged at its upper end and journaled upon a tubular support 35 which is rigidly secured at its front end in the bracket 8 and has 100 a stationary arm 36 secured in position upon its rear end by a clamping bolt 37.

The lower part of the rock arm 33 is provided with an intake passageway 38 and a discharge passageway 39 which communicate with the intake port 31 and the discharge port 32, respectively, through two passageways 40 and 41 formed axially in the pintle 23.

The passageways 38 and 39 are connected, respectively, through two tubes 42 and 43 to an intake passageway 44 and a discharge passageway 45 formed in the upper end of the stationary arm 36.

The intake passageway 44 has the low pressure supply pipe 14 connected thereto and the discharge passageway 45 is connected by an outlet pipe 46 to the control valve 15, as shown diagrammatically in Fig. 2.

The tubes 42 and 43 have their upper ends rounded and fitted in concave seats 47, which are formed in the upper end of the stationary arm 36 in alignment with the passageways 44 and 45, and their lower ends rounded and fitted in concave seats 48, which are formed in plungers 49 fitted in the enlarged upper ends of the passageways 38 and 39.

The rounded ends of the tubes 42 and 43 are held in firm engagement with the seats 47 and 48 by the fluid pressure against the inner ends of plungers 49, and also by helical compression springs 50, one of which is arranged between the lower end of each plunger 49 and a shoulder 51 formed in each of the passageways 38 and 39.

The tubes 42 and 43 thus provide flexible connections for the flow of liquid between the lower end of the rock arm 33 and the upper end of the stationary arm 36 and allow the arm 33 to be rocked upon the support 35 without affecting this flow of liquid.

The gear pump draws liquid from the reservoir 2 through the pipe 13 and delivers it through the pipe 14, the passageway 44, the tube 42, the passageway 38, the passageway 40 and the intake port 31 to the cylinders 21. Liquid is discharged from the cylinders 21 through the outlet port 32, the passageway 41, the passageway 39, the tube 43, the passageway 45 and the pipe 46 to the valve 15; the pressure created by the variable displacement pump being limited by a high pres-

140

135

145

150

sure relief valve 52 which is connected to the pipe 46 and discharges into the reservoir 2.

In the prior pump, the cylinder barrel is ordinarily made of cast iron and the pintle of steel but, in the present invention, the pintle is made of a metal, such as brass or bronze, which has a much higher coefficient of expansion than the cast iron of which the cylinder barrel is made. Consequently, an increase in temperature 10 will cause the pintle to have a greater diametral expansion than the cylinder barrel with the resultant reduction in the clearance between the same, and this reduction in clearance corresponds substantially to the reduction in the viscosity of 15 the oil throughout the range of ordinary operating temperatures, for instance, up to 140° F.

In other words, the pintle expands and reduces the clearance between itself and the cylinder barrel in response to increases in temperature 20 and thereby prevents a substantially greater amount of oil from escaping when the pintle and the oil are heated than can escape when both are cold.

In actual practice, the pintle and the bore of 25 the cylinder barrel are tapered slightly and lapped to a close fit, and then the cylinder barrel is adjusted upon the pintle to provide the closest possible running fit when the pintle and the cylinder barrel are heated to the highest temperature which may be encountered in service, 30 for instance 160° F., at which time the oil is thinnest and provides a very thin lubricating film between the cylinder barrel and the pintle.

For example, a common size pump has a 1 $\frac{7}{8}$ " 35 diameter bronze pintle and a cast iron cylinder barrel fitted thereon to provide a clearance of about .0006 inches when hot. If a considerably larger or smaller pintle is employed, materials are selected which have the correct relative 40 thermal characteristics.

A reduction in temperature causes an increase 45 in the clearance between the cylinder barrel and the pintle and a corresponding increase in the viscosity of the oil so that the amount of slip remains substantially constant throughout the entire range of operating temperatures.

As the metals which are otherwise suitable for pintle construction are usually too soft to provide high resistance to the wear thereon, the 50 pintle is preferably provided with a shell or covering 53 of hard metal, such as chromium, to resist the wear thereon and this covering is generally applied by plating the pintle with chromium and then grinding and fitting it to the cylinder 55 barrel.

The stroke of the pump may be changed, to obtain accurately graduated changes in displacement, by operating a control lever 54 secured upon the front end of a control shaft 55 which is journaled in the front plate 3 and has a locking lever 56 threaded thereon for securing it in adjusted 60 positions.

The control shaft 55 extends rearwardly 65 through the tubular support 35 and it is held against axial movement by a collar 57 and a gear 58 which are secured thereon in engagement, respectively, with the front and rear ends of the support 35.

The gear 58 meshes with an idler gear 59 which 70 is arranged upon a shaft 60 carried by the rock arm 33, and the gear 59 meshes with a gear 61 journaled upon a shaft 62 which is carried by the pintle 23 at the rear end thereof.

The hub 63 of the gear 61 is eccentric to the 75 axis of the shaft 62 and has an eccentric head 64

journaled thereon and provided with a threaded lateral bore 65 to receive the threaded end of a thrust pin 66. The head 64 is bifurcated along one side of the bore 65 and provided with a bolt 67 for clamping the thrust pin 66 in adjusted positions. 80

The head of the thrust pin 66 abuts the inner end of a recess 68 formed in the front end of a plunger 69 which is provided upon its rear end with a guide pin 70 and arranged for reciprocation in a bore 71 formed in a piston 72 and in the stem 85 73 thereof.

The piston 72 is fitted in a cylinder 74, which is carried by the lower end of the stationary arm 36 and closed at its inner end by an integral head 75 and at its outer end by a cap 76, and the stem 90 73 extends through the head 75 and is fitted therein to prevent the escape of liquid from the cylinder 74.

The piston 72 is urged against the head 75 by a helical compression spring 77 which abuts the inner face of the cap 76 and is arranged in an annular recess 78 formed in the piston 72. 95

The plunger 69 is urged outwardly against the thrust pin 66 by a stack of Belleville spring washers 79 which are arranged in the bore 71 between 100 the inner end thereof and the plunger 69.

The piston 72 has a bore 80 of smaller diameter than the bore 71 and coaxial therewith to receive a helical compression spring 81 which holds the washers 79 against movement relatively to the 105 plunger 69 when the piston 72 is retracted. A still smaller bore 82 in the outer end of the piston 72 receives the end of the guide pin 70 which extends through the washers 79 and the spring 81.

The cylinder 74 is connected by a duct 83, which 110 is formed in the arm 36, to a pipe 84 which is connected to the control valve 15 as shown diagrammatically in Fig. 2, and the control valve 15 may be operated to direct liquid from the gear pump to the cylinder 74 to retract the piston 72 115 against the resistance of the spring 77.

Retraction of the piston 72 allows the pump to increase its stroke until a lug 85 on the rock arm 33 engages a stop bolt 86, as will be described hereinafter. The bolt 86 is threaded into the stationary arm 36 and is adjusted to arrest further movement of the arm 33 when full stroke or a predetermined maximum displacement has been reached. 120

As previously stated, the gear pump has a larger 125 volumetric capacity than the variable displacement pump and delivers liquid to the intake of the variable displacement pump so that it maintains in the passageways 40 and 44 a pressure determined by the adjustment of the relief valve 16. 130

This liquid acts upon the opposed walls of the passageways 40 and 44 and tends to separate them, thereby tending to swing the rock arm 33 upon the support 35 and holding the thrust pin 66 in engagement with the plunger 69. 135

When the variable displacement pump is delivering liquid under pressure, the liquid in the passageways 39 and 45 acts upon the opposed walls thereof and likewise tends to swing the rock arm 33 upon the support 35 and, when the pressure of 140 the discharge liquid becomes high enough to cause an appreciable increase in the slip of the pump, the force exerted by the discharge liquid is sufficient to compress the Belleville washers and swing the lower end of the arm 33 toward the piston 72 145 to increase the stroke of the pump a corresponding amount and thereby increase the volume of liquid discharged from the cylinders an amount which is substantially equal to the increase in slip. 150

As variations in temperature cause variations in the diameter of the pintle with the resultant variations in the clearance between the pintle and the cylinder barrel, so that the slip of the 5 pump is maintained substantially constant at any given temperature, and as the pump automatically compensates for variations in slip caused by variations in pressure, the net discharge of the 10 pump remains substantially constant throughout the entire range of operating pressures and temperatures.

The stroke of the pump is adjusted manually by loosening the locking lever 56 and operating the control lever 54 to rotate the gears 58, 59 and 15 61. Rotation of the gear 61 causes its eccentric hub 63 to move the head 64 and the thrust pin 66 toward or from the piston 72.

The hub 63 is shown in the drawings, and 20 particularly in Fig. 3, with its thick part toward the thrust pin 66 so that the pump is at zero stroke. When the hub 63 is rotated, the distance between the axis of the shaft 62 and the outer end of the thrust pin 66 is shortened and the 25 pressure of the discharge liquid swings the lower end of the arm 33 toward the piston 72 and increases the stroke of the pump, and the eccentricity of the hub 63 is ordinarily such that the pump is on full stroke when the thinnest part of the hub 63 is toward the thrust pin 66.

30 However, the pump is adapted to operate hydraulic mechanisms at various speeds, for instance, to operate the feeding mechanism of a machine tool at both feeding and rapid traverse speeds.

35 In such a case, the pump is adjusted to deliver a volume of liquid considerably below its capacity to operate the mechanism at feeding speed and the control valve is operated to direct liquid from the gear pump into the cylinder 74 at 40 certain intervals.

When the gear pump liquid enters the cylinder 74, it retracts the piston 72 and the pressure of the discharge liquid swings the arm 33 to put the pump on full stroke, thereby instantly increasing the delivery of the pump from a predetermined minimum volume to its full volumetric capacity or to a maximum volume which is determined by the adjustment of the stop bolt 86. When the valve 15 is operated to disconnect 45 the cylinder 74 from the gear pump, the spring 77 sets the pump back instantly to the predetermined stroke.

The invention herein set forth is susceptible of various modifications and adaptations without 55 departing from the scope thereof as hereafter claimed.

The invention is hereby claimed as follows:

1. In a pump having driving and driven members eccentric to each other, the combination of 60 means responsive to the pressure created by said pump for increasing the eccentricity of said members to thereby increase pump displacement, means resisting the action of said pressure responsive means and yieldable under the influence of pressures above a predetermined minimum to enable said pressure responsive means to increase the stroke of said pump an amount sufficient to compensate for the increase in the slip of said pump caused by the increase in said 65 pressure, and hydraulically operated means for retracting said action resisting means to increase the stroke of said pump to a predetermined maximum.

2. A radial inflow pump, comprising a support, 75 a rock arm carried by said support and having

intake and discharge passageways, a pintle carried by said rock arm and having intake and discharge ports and passageways communicating with the intake and discharge passageways in said rock arm, a cylinder barrel journaled upon said pintle and having cylinders arranged radially thereto and provided with ports for registering with said intake and discharge ports alternately, pistons fitted in said cylinders, a driver for reciprocating said pistons, means for rotating said driver, a stationary arm carried by said support and having intake and discharge passageways, an expansion joint connecting each passageway in said rock arm to one of the passageways in said stationary arm and spaced from the axis of said support to enable the pressure created by said pump to tend to rotate said rock arm upon said support and swing its free end toward the free end of said stationary arm and thereby increase the stroke of said pump, and means carried by the free end of said stationary arm to resist the movement of said rock arm and yieldable to enable said pump pressure to increase the stroke of said pump after said pressure has increased above a predetermined minimum to thereby compensate for the increase in the slip of said pump caused by said increase in pressure.

3. A radial inflow pump, comprising a support, a rock arm carried by said support and having intake and discharge passageways, a pintle carried by said rock arm and having intake and discharge ports and passageways communicating with the intake and discharge passageways in said rock arm, a cylinder barrel journaled upon 105 said pintle and having cylinders arranged radially thereto and provided with ports for registering with said intake and discharge ports alternately, pistons fitted in said cylinders, a driver for reciprocating said pistons, means for rotating said driver, a stationary arm carried by said support and having intake and discharge passageways, an expansion joint connecting each passageway in said rock arm to one of the passageways in 110 said stationary arm and spaced from the axis of said support to enable the pressure created by said pump to tend to rotate said rock arm upon said support and swing its free end toward the free end of said stationary arm and thereby increase the stroke of said pump, a cylinder carried by the free end of said stationary arm, a piston arranged in said cylinder, a spring urging 115 said piston against the head of said cylinder, a plunger arranged in said piston, a thrust pin carried by said rock arm and engaging said plunger and spring means urging said plunger against said thrust pin and adapted to be deflected by said rock arm in response to a predetermined increase in the pressure created by said pump to increase the stroke of said pump and thereby compensate for the increase in the slip of said pump caused by said increase in pressure.

4. A radial inflow pump, comprising a support, a rock arm carried by said support and having intake and discharge passageways, a pintle carried by said rock arm and having intake and discharge ports and passageways communicating with the intake and discharge passageways in said rock arm, a cylinder barrel journaled upon 120 said pintle and having cylinders arranged radially thereto and provided with ports for registering with said intake and discharge ports alternately, pistons fitted in said cylinders, a driver for reciprocating said pistons, means for rotating said driver, a stationary arm carried by said support and having intake and discharge passageways, an expansion joint connecting each passageway in said rock arm to one of the passageways in 125 said stationary arm and spaced from the axis of said support to enable the pressure created by said pump to tend to rotate said rock arm upon said support and swing its free end toward the free end of said stationary arm and thereby increase the stroke of said pump, a cylinder carried by the free end of said stationary arm, a piston arranged in said cylinder, a spring urging said piston against the head of said cylinder, a plunger arranged in said piston, a thrust pin carried by said rock arm and engaging said plunger and spring means urging said plunger against said thrust pin and adapted to be deflected by said rock arm in response to a predetermined increase in the pressure created by said pump to increase the stroke of said pump and thereby compensate for the increase in the slip of said pump caused by said increase in pressure.

port and having intake and discharge passageways, an expansion joint connecting each passageway in said rock arm to one of the passageways in said stationary arm and spaced from the axis 5 of said support to enable the pressure created by said pump to tend to rotate said rock arm upon said support and swing its free end toward the free end of said stationary arm and thereby increase the stroke of said pump, means carried 10 by the free end of said stationary arm to resist the movement of said rock arm and yieldable to

enable said pump pressure to increase the stroke of said pump after said pressure has increased above a predetermined minimum and thereby compensate for the increase in the slip of said pump caused by said increase in pressure, and 80 hydraulic means for retracting said movement resisting means to enable said pressure to increase the stroke of said pump to a predetermined maximum.
